ADJUSTABLE CRUTCH

Otto Bostelman, Defiance, Ohio

Application July 30, 1952, Serial No. 301,766

3 Claims. (Cl. 135—49)

1

The present invention relates to improvements in adjustable crutch and has for an object to provide a crutch in which the leg or knee rest is adjustable vertically for the purpose of equalizing height and adjustable horizontally to widen or narrow the leg or knee rest for the accommodation of large or small knees.

It is another object of the invention to provide a variety of adjustments both vertical and horizontal by which the leg or knee rest may be made to assume various elevations, various widths and deeper or shallower concave forms for the accommodation of short and tall persons, those having wide or narrow knees, in which all adjustments contribute to the comfort of the patient using the improved crutch.

It is a further object of the invention to provide an improved crutch useful to a person having an injury below the knee, such crutch providing a leather strap or other flexible support or leg or knee rest, to the end that with this crutch the average person can walk more conveniently and execute other bodily maneuvers with normal facility, to such degree that the patient requires only one crutch rather than two.

The invention also contemplates a form of crutch in which a brace may be adjusted angularly with respect to the main staff for the purpose of adjusting the span of the leg or knee rest which stretches between the staff and this brace with a spreader arrangement which will maintain the angle of adjustment and at the same time provide a truss arrangement in combination with included portions of the brace and staff to reinforce the support that the upper end of the brace gives to the flexible leg or knee support.

It is a further object of the invention to provide an improved crutch having the above construction and objects and purposes whereby the large number of adjustments, subject to simultaneous imposition, will permit a very exact fitting of the leg or knee brace to the limb of the patient.

With the foregoing and other objects in view, the invention will be more fully described hereinafter, and will be more particularly pointed out in the claims appended hereto.

In the drawings, wherein like symbols refer to like or corresponding parts throughout the several views.

Figure 1 is a perspective view of an improved adjustable crutch constructed in accordance with the present invention;

2

Figure 2 is a fragmentary perspective view taken on an enlarged scale showing details of adjustable leg rest, spreader and the bolt;

Figure 3 is a fragmentary perspective view taken on a still larger scale, with parts broken away and parts shown in section showing the spreader block and its connection with the staff and brace;

Figure 4 is a horizontal section taken on the line 4—4 of Figure 3;

Figure 5 is a front elevational view of the lower portion of the crutch, with parts broken away and parts shown in section;

Figure 6 is a magnified view of the crutch at the leg rest showing an adjustment of the leg rest on a large radius;

Figure 7 is a vertical section taken on the line 7—7 of Figure 2;

Figure 8 is a fragmentary perspective view similar to Figure 3, showing a modification;

Figure 9 is a view similar to Figure 5 showing a further modified form; and

Figure 10 is a horizontal section taken on an enlarged scale on the line 10—10 of Figure 9.

Referring more particularly to the drawings, 10 designates the staff of the crutch which may be made of wood or other appropriate material having substantial rigidity for sufficiency of support, and 11 represents a diagonal brace, which may be of wood or some other material preferably possessing some inherent resiliency.

The leg rest or cradle 12 is formed by flexible material, for instance leather which may lend itself appropriately to the adjustments herein-after referred to.

The lower end of the diagonal brace 11 parallels the lower portion of the staff 10 to which it is secured by bolts or other fastenings 13. Above the parallel section the diagonal brace 11 diverges from the staff 10. Due to the inherent resiliency of the brace 11 a resilient hinge 14 is produced at or about the point of divergence to permit the angle of divergence to be altered for the purpose of moving the upper free end of the brace 11 nearer to or farther from the staff 10.

In the staff 10 are produced a series of vertical perforations 15 to match a similar vertical series of perforations 16 at similar heights in the diagonal brace 11. Bolts and nuts 17 and 18 or other fastenings respectively secure the leg rest to the staff 10 and to the diagonal brace 11, the bolts 17 and 18 passing through selected perforations 15 and 16. Such bolts 17 and 18 also pass through selected perforations of series of perfora-

tions 33 and 34 in the opposite end portions of the leg rest 12.

The diagonal brace 11 is biased resiliently to a preselected minimum angle with respect to the staff 10 and such brace 11 may be moved outwardly to enlarge this angle by a spreader 19 which may be made of wood or other appropriate material and which will hold the brace at the selected enlarged angle. A tie bolt 20 is connected between the staff 10 and the brace 11 to draw these parts together upon the spreader. The tie bolt 20 is provided with a bolt head 21 and a nut 22 which may be countersunk in the staff 10 and the diagonal brace 11. Such recesses are indicated at 23 and 24. The bolt head takes one recess 23 while the nut 22 engages against the base of the nut recess 24.

If desired pins 25 with sharpened ends may project from the ends of the spreader 19 to take into the wood of the staff and brace. Also there may be vertical grooves 26 and 27 in the staff 10 and brace 11 of sufficient horizontal width to permit the pins 25 to slide up and down therein, the side walls of such grooves 26, 27 confining the pins 25 and the spreader 19 into correct relationship with the adjacent walls of the staff 10 and brace 11. In the bases of the grooves 26 and 27 there may be produced vertically spaced sockets 28 to receive the pins 25. Such spaced sockets 28 will form stepped adjustment pockets for the pins 25.

The modified form of spreader 30 shown in Figures 9 and 10 is held in place by the bolt 29 which passes through the spreader 30. The ends of this bolt 29 are vertically adjustable in vertically elongated slots 31 and 32 in the staff 10 and brace 11, respectively. By tightening the nut 35 the bolt 29 will draw the brace 11 against the outer end of the spreader 30 and will move the other end of the spreader tightly against the staff 10.

In the use of the device, one adjustment may be secured by arranging the bolts 17 and 18 in the upper perforations 33 and 34 of the leg rest 12 and passing such bolts through selected perforations of the vertical series 15 and 16 in the staff and brace. This adjustment will not materially change the radius of curvature of the leather leg rest. In other words the leg rest or cradle 12 will remain of approximately the same width but its height will be altered. The concavity of the surface of the leg rest or strap cradle 12 will remain the same through these adjustments. A second adjustment may be had by arranging the bolts 17 and 18 in selected perforations 15 and 16 and then changing the perforations 33 and 34 of the leg rest which engage such bolts 17 and 18. For instance if the uppermost or outermost perforations 33, 34 are engaged by the bolts 17, 18 then a larger length of the strap or leg rest 12 will extend between the bolts 17 and 18 and this larger length will dip down to a maximum deep concave surface. By engaging with the bolts 17, 18 the next lower perforations 33, 34 of the leg rest 12, such leg rest will be shortened and flattened. The adjustment provided by the innermost perforations 33, 34 may be so arranged as to stretch the leather leg rest 12 across between the staff in a substantially flatwise or horizontal position.

A third adjustment is provided by varying the first two adjustments above mentioned. For instance in the maximum flat condition of the leg rest 12 in which the same is supported by the bolts 17, 18 from the innermost of the perfora-

tions 33, 34, such bolts 17 and 18 may be moved up and down in the series of perforations 15 and 16 in the staff and brace to vary the height of the flat leg rest 12. In descending in the scale of vertical perforations 15, 16 the flatness or stretched condition of the leather leg rest 12 will be relaxed step by step.

Other adjustments may be made by engaging the bolts 17, 18 with relatively different perforations 15, 16 and 33, 34. For instance the bolt 17 might be engaged in the top perforation 15 while the bolt 18 is engaged in the second from the top perforation 16. Also the bolt 17 may be engaged in the second from the outermost perforation 33 of the leg rest 12 while the bolt 18 is engaged with the outermost perforation 34 at the other side of the leg rest.

A fourth adjustment is provided by shifting the spreader 19, 30 up or down by means of the 20 adjustment of the respective tie bolts 20, 29 in order to move the upper perforated end of the diagonal brace 11 nearer to or farther from the opposed perforated section of the staff 10. When the brace moves toward the staff the concavity 25 of the leg rest 12 will be deepened, that is, the radius of the same will become of less length; and when the diagonal brace 11 is moved farther from the staff 10, the leg rest 12 will tend to a more flattened condition.

30 All of the above adjustments may be simultaneously imposed upon the leg rest 12. Therefore, a large number of adjustments are provided both to raise and lower the leg rest 12 and also to provide a deeply concave surface or a surface 35 tending to be more flat. The device, therefore, provides accommodations for large or small knees. The knee socket in the leg rest 12 is also adjustable as to height.

Although I have disclosed herein the best form 40 of the invention known to me at this time I reserve the right to all such modifications and changes as may come within the scope of the following claims.

What I claim is:

45 1. A crutch comprising a staff, a diagonal brace secured to the lower end of the staff and diverging upwardly away from the staff, means slideable up and down between the staff and brace for moving the upper portion of the brace toward and away from the staff, a flexible leg rest, fastenings for supporting opposite end portions of the leg rest respectively on said staff and upper portion of the brace, means on the staff and brace for adjusting the fastenings to various vertical elevations, and means on the flexible leg rest for 50 adjusting the length of leg rest between the fastenings to create different degrees of curvature in the leg rest.

60 2. A crutch comprising a staff, a leg rest hingedly related to the lower portion of the staff and diverging upwardly with relation to the staff, a flexible leg rest, fastenings for suspending the leg rest across the gap between the upper portion of the brace and the opposed part of the staff, means on the staff and brace for accom-

65 modating said fastening means at various elevations, means to vary the angle of the brace with reference to the staff to slacken or taunt the leg rest in its suspended condition between staff and brace, and means for selectively shortening and lengthening the flexible leg rest between fastenings to change its radius of curvature as suspended between the fastenings.

70 3. A crutch comprising a staff, a diagonal brace hinged at its lower portion to the staff and di-

verging upwardly therefrom, a wedge block having end portions engaging inner surfaces of the brace and staff and adapted to be wedged downwardly to move the brace about its hinged connection outwardly away from the staff, means for retaining the wedge block in adjusted position, a flexible leg rest, fastenings between which the leg rest is suspended from the upper portion of the brace to the opposed part of the staff, means for adjusting said fastenings vertically in 10 the staff and brace, and means whereby different lengthwise portions of the leg rest are selectively engaged with the fastenings to shorten or length-

en the suspended portion of the leg rest between the fastenings.
